PORTABLE GRINDING MACHINE

John P. McNeil, Tucson, Ariz.

Application May 2, 1935, Serial No. 19,475

7 Claims. (Cl. 51—166)

This invention relates to a portable grinding machine capable of assuming a very compact form when not in use and adapted to be carried in a manner similar to a suitcase or the like.

5 It is particularly aimed to provide such a construction which will be relatively light in weight and will furnish all of the necessary equipment for the prompt grinding or sharpening of knives, scissors or other implements or tools.

10 The more specific objects and advantages will become apparent from a consideration of the description following taken in connection with accompanying drawings illustrating an operative embodiment.

15 In said drawings:—

Figure 1 is a perspective view of the device in its portable condition;

Figure 2 is a cross sectional view taken on the line 2—2 of Figure 1;

20 Figure 3 is a plan view of the device;

Figure 4 is a side elevation of the device;

Figure 5 is a vertical sectional view taken on the plane of line 5—5 of Figure 3;

25 Figure 6 is a vertical sectional view taken on the plane of line 6—6 of Figure 3;

Figure 7 is a view substantially similar to Figure 6, with the grindstone support retracted;

Figure 8 is a detail section illustrating the mounting of the upper crank driven by the treadle;

30 Figure 9 is a cross sectional view taken on the line 9—9 of Figure 5;

Figure 10 is a detail section taken on the line 10—10 of Figure 5; and

35 Figure 11 is a vertical sectional view through a modified form of the invention.

Referring specifically to the drawings, wherein like reference characters designate like or similar parts, 10 designates a casing, housing or the like of any suitable size, shape and material, for instance, of wood or metal. One side wall 11, of said housing, is hinged to the housing as at 12 so that it may be opened or closed to give access to the parts when desired.

40 In addition, hasps 13 are pivoted to the inner side of the wall or closure 11 and are engageable with staples 14, carried by the adjacent walls of the housing. Any suitable means, if desired, may be used to secure the hasps 13 to the staples

45 against accidental detachment. Such wall or closure 11 has a bar 15 attached thereto, in turn having a handle 16, secured adjustably thereto by means of bolts 17, passing through elongated slots 18 in the bar and handle, the bolts having wing nuts 19. The adjustable mounting of the

handle 16 enables it to be fastened in different positions for balancing according to the load or distribution thereof within the casing 10.

One end wall 20 is removable, having a continuous flange 21 whereby such wall is telescoped over one end of the casing, including the closure 11, whereby the latter cannot accidentally open. Staples 22 are provided adjacent the closure 20 on the side wall of the casing, and they are engaged by hooks 23 pivoted at 24 to hasps 25, pivoted at 26 to said closure 20.

The purpose of having the closure 20 removable is to enable a supporting table 27 for the grinding tool to be projected from the normally retracted position shown in Figure 7 to the position shown in Figure 6. Such table has a pair of U-shaped brackets 28 fastened thereto, whose legs 29 have elongated slots 30^a therethrough. Cleats 31^a are fastened to the casing 10 behind the legs 29 and they mount bolts 32^a which pass through the slots 30^a and beyond the same receive winged nuts 33 by means of which the table may be rigidly fastened either in the retracted position of Figure 7 or the projected position of Figure 6.

Said table 27 is suitably cut away, to enable a bracket or mounting 28^a to engage the same and be removably clamped thereto through the medium of a screw 29^a carried by the bracket or mounting. A shaft 30 is journaled in the mounting 28^a and it removably carries a tool 31 shown as a grinding tool and for instance such as an emery wheel or ordinary grindstone. Obviously, the invention may be used in connection with other tools and hence the showing at 31 is to be taken as broad since the shaft 30 may be used to operate a disk saw, a drill, or other tool. Keyed to the shaft 30 is a gear wheel 32 enmeshed with a gear wheel 33 carried by a shaft 34 also journaled in the mounting 28^a. Shaft 34 projects beyond one side of the mounting 28^a and has a pulley 35 fastened thereto. Over said pulley 35 a belt 36 is trained, which passes through the table 27 in view of its slotting at 37, and traverses a pulley 39 within the casing. A guard or protecting housing 40 is disposed over the pulley 35 and adjacent parts, being fastened as at 41 to the mounting 28^a. Said pulleys 35 and 39 are preferably grooved to better retain the belt.

Said pulley 39 is keyed to a cross shaft 42 journaled at opposite ends by bearing means 43 and 44. Said shaft 42 has a crank 45 with which a pitman 46 is pivoted and which in turn is pivoted at its lower end at 47 with a treadle 48, rigid on a rock shaft 49, also journaled by suitable

bearing devices 50 and 51, identical with those at 43 and 44, respectively. Since it usually is necessary for a mechanic to be skillful to operate the device through one treadle 48, I provide a second treadle at 52. Such treadle 52 is pivoted at 53 to the rock shaft 49 in a manner to limit unfolding of the treadle 52 into alignment with the treadle 48. Thus a treadle is provided for operation by each foot. Ordinarily, the casing 10 is not of a size to permit the use or presence of two treadles within the same. Said treadle 52 is normally folded flat against the outside of the casing as in Figures 1, 2, and 5, being held by a releasable spring finger 54.

15 Reverting to the bearing devices generally designated 43 and 50, they are preferably of the form shown in Figure 9. The shafts 42 and 49, are connected to ball-bearing cages within such devices and the devices consist of plates 55 rigidly fastened to the wall of the casing and plates 56, which are the upper ones, detachably bolted as at 57 to said plates 55. Said plates are bulged as at 58 and 59 respectively, in order to enclose the ball bearing races.

20 25 As I have found that bolts or the like interfere with movement of the foot on the treadle 48, I preferably use the form of bearing device shown in Figure 10, at 44 and 51. This device comprises a section or plate 60 suitably fastened to the wall 30 of the casing 10, and slidably receiving a plate 61. Plate 61 is insertable from above and is guided and retained by flanges 62 integral on the plate 60. Such plates 60 and 61 have bulged portions 63 and 64, which retain the ball bearing 35 races connected to the respective shafts 42 and 49.

40 It will be seen that the device may be transported from place to place in the manner of a suit-case in view of its provision with a handle 16 and the compact construction and arrangement of the parts. When using the device, it is stood on one end, treadle 52 lowered, and closure 20 removed, table 27 projected, and the mounting 28a and the associated parts positioned operatively as in Figures 3, 4, 5, and 6, for example. Thereupon the treadles may be operated to impart motion through the gearing shown to the tool 31.

45 It is clear that various changes may be resorted to within the spirit and scope of the invention. For instance, I do not limit myself to any particular gearing for operating the shaft 30 and tool from the treadle, hence for example, chain and sprocket means may be substituted 50 for the parts 35, 36 and 39 or various types of gearing may be used.

55 For instance, I may employ the form of Figure 11 wherein bevel gears are used in lieu of the chain and sprocket. Also shaft 42' which corresponds to shaft 42 and shaft 34' which corresponds to shaft 34 may respectively be provided with beveled gear wheels 70 and 71. A shaft 72 is journaled in brackets 73 and 74 fastened to the housing, and it has beveled gear wheels 75 and 76 enmeshed with the gear wheels 70 and 34', respectively.

60 Said shaft 72 is in telescopic section so that the upper section may be removed with the grinding or tool assembly to permit the table 70 to be positioned within the casing and the end wall applied therover.

65 It will be understood that the grinding or other tool and mounting when detached, together with other tools or accessories desired by the owner, 70 may be carried within the casing 10.

I claim as my invention:

1. A device of the class described having a casing, a removable end wall on said casing, a side wall of said casing being movable to open position, and said end wall having a flange overlapping said side wall to normally prevent opening thereof, a table, and means mounting said table normally within the casing and for projection through the open end of the casing when said end wall is removed. 10

2. A device of the class described having a casing, a removable end wall on said casing, a side wall of said casing being movable to open position, said end wall having a flange overlapping said side wall to normally prevent opening 15 thereof, a table, means mounting said table normally within the casing and for projection through the open end of the casing when said end wall is removed, said table having depending legs, and bolt means carried by the casing 20 coacting with said legs to secure them in the different positions.

3. A device of the class described having a casing, a removable end wall on said casing, a side wall of said casing being movable to open position, said end wall having a flange overlapping said side wall to normally prevent opening thereof, a table, means mounting said table normally within the casing and for projection through the open end of the casing when said end wall is removed, a tool device removably applicable to the table in its projected position, and gearing for said tool device operative from within the casing. 30

4. A device of the class described having a casing, a removable end wall on said casing, a side wall of said casing being movable to open position, said end wall having a flange overlapping said side wall to normally prevent opening thereof, a table, means mounting said table normally within the casing and for projection through the open end of the casing when said end wall is removed, a tool device removably applicable to the table in its projected position, and gearing for said tool device operative from within the casing comprising cross shafts, a pitman connected to one of said shafts, a treadle pivoted to the other shaft and to said pitman, and driving means from one of said shafts to said tool device. 40

5. A device of the class described having a casing, a removable end wall on said casing, a side wall of said casing being movable to open position, said end wall having a flange overlapping said side wall to normally prevent opening thereof, a table, means mounting said table normally within the casing and for projection through the open end of the casing when said end wall is removed, a tool device removably applicable to the table in its projected position, and gearing for said tool device operative from within the casing comprising cross shafts, a pitman connected to one of said shafts, a treadle pivoted to the other shaft and to said pitman, and driving means from one of said shafts to said tool device, said tool device comprising a 55 mounting detachably connected to said table.

6. A device of the class described having a casing, a removable end wall on said casing, a side wall of said casing being movable to open position, said end wall having a flange overlapping said side wall to normally prevent opening thereof, a table, means mounting said table normally within the casing and for projection through the open end of the casing when said end wall is removed, a tool device removably 70

75

applicable to the table in its projected position, gearing for said tool device operative from within the casing comprising cross shafts, a pitman connected to one of said shafts, a treadle pivoted to the other shaft and to said pitman, and driving means from one of said shafts to said tool device, said tool device comprising a mounting detachably connected to said table, a treadle pivoted to the last mentioned shaft exteriorly of the casing, said last mentioned treadle being foldable against the casing, and means on the

casing to hold said treadle in its folded position.

7. A device of the class described having a casing, means to mount a tool thereon, driving means for said tool including a rock shaft, a treadle fastened to the rock shaft, a treadle pivoted to the rock shaft exteriorly of the casing and foldable against the casing, and means to releasably secure the second mentioned treadle against the casing. 5
